UNITED STATES PATENT OFFICE.

CHARLES S. SMITH, OF CHICAGO, ILLINOIS.

FOOTREST.

Application filed January 12, 1923. Serial No. 612,249.

To all whom it may concern:

Be it known that I, CHARLES S. SMITH, a citizen of the United States, residing at Chicago, in the county of Cook and State of Illinois, have invented certain new and useful Improvements in Footrests, of which the following is a specification.

This invention relates to a footrest for a shoe shining stand whereon is a chair for the customer, and in particular it is concerned with certain improvements by which a pair of supports for the feet are mounted so as to be slideable forwardly and rearwardly of the chair as desired.

An embodiment of this invention in a preferred form is shown in the accompanying drawings wherein:

Figure 1 is a horizontal section through a chair pedestal taken on line 1—1 of Fig. 2, looking down upon a platform whereon are mounted a pair of foot rests;

Fig. 2 is a side elevation of the pedestal and platform showing also the proximate foot rest mounted thereupon;

Fig. 3 is an enlarged detail through the mounting wherein one of the foot rests is slidably received;

Fig. 4 is a transverse section therethrough on line 4—4 of Fig. 3;

Fig. 5 is a horizontal section taken on line 5—5 of Fig. 3;

Fig. 6 is a detail in perspective of the shoe which is adjustably held within the mounting;

Fig. 7 is a horizontal section on line 7—7 of Fig. 8, and is similar to Fig. 1, except that the mountings for the foot rests are connected directly to the chair pedestal;

Fig. 8 is a side elevation thereof;

Fig. 9 is an enlarged detail in side elevation showing one mounting with its removable cover plate taken off; and

Fig. 10 is a transverse section taken on line 10—10 of Fig. 9.

In the drawing is shown a chair pedestal A adapted for mounting upon the usual platform B of a shoe shining stand. As shown in Figs. 1 and 2, a pair of adjustable foot rests C are also mounted upon the platform, one on each side of the pedestal. Any suitable construction of chair, platform, etc., may, of course, be employed.

The present invention is concerned entirely with the foot rest and its mounting, which, in the form shown, consists of a frame D in the form of an inverted box

having front and rear walls 11 and 12, respectively. Extending laterally from the base of the frame are outturned ears 13 through which screws 14 or other attaching 60 mediums may be inserted to fasten the frame securely to the platform.

Extending forwardly from the front wall of the frame is a base flange 15 on which is rested a block 16 which may be conveniently 65 secured in place as through the medium of one or more screws 17. In the front wall is provided a slot 18, the lower end of which terminates substantially flush with the upper face of the block, and in the rear wall 12 is 70 another registering slot 19, slightly longer, but otherwise very similar. Through these two frame slots is slidably received a bar 20 having a cross section which is generally the same as the slot openings. At the forward end of the bar is carried one of the 75 foot rests C, while a stop member 21 is preferably arranged to the rear end thereof.

Formed in the upper face of the bar are a series of transverse notches 22 any one of which is adapted to co-operate with the lower edge of a locking plate 23 which is preferably secured within the frame against the inner side of its rear wall just above the slot 19, a screw 24, or other equivalent device, being employed to hold the plate in place. A plate of this kind may have its lower edge appropriately formed to engage successively within each of the bar notches 22 as the bar is shifted lengthwise of the 80 frame. To effect a shift in the position of the bar it is necessary merely that its forward end be lifted slightly to thereby lower its rear end sufficiently to effect a disengagement from the locking plate, following 85 90 95 which the bar may be shifted longitudinally to a desired position.

It is apparent that with repeated adjustments of the bar those portions of the frame wall which are mainly subject to friction will 100 become worn, particularly if the frame be made of brass or any other material which lends itself readily to a high polish or ornamental finish. According to my construction the block 16 suffices to resist the wear 105 which would otherwise take place at the lower end of the slot 18, and likewise the plate 23, which may be made of hardened metal, is ample to resist the wear at the upper end of the slot 19. Along their sides, 110 however, the slots are not protected and in course of time might become so worn that

the bar will play therein to an undesirable extent.

To offset any such tendency, I have provided a channeled shoe 25 having upper and lower flanges 26 and 27 adapted to overlie the corresponding edges of the bar. This shoe is positioned within the frame and is provided with an outwardly extended boss 28 in which may be formed an opening 29 adapted to receive the thrust end 30 of a set-screw 31 which passes through a threaded opening 32 in the frame side. A lock nut 33 may also be employed to maintain the set screw in any desired position of adjustment. 15 By the means suggested the shoe may be held at all times against one side of the bar 20 with a desired degree of pressure, the purpose being to prevent play of the bar within the two slots which form the guideway 25 therefor. As wear takes place, the shoe may 20 further adjusted to compensate.

A construction answering to the preceding description may be employed with considerable advantage, but may also be modified 25 within considerable limits, a suggestive construction being exhibited in Figs. 7 to 10 inclusive. Here is shown a platform B whereon is mounted a chair pedestal A carrying on each of its opposite sides a mounting D 30 for a slideable foot rest C similar in all respects to the construction hereinbefore set forth.

Each bar mounting comprises, by preference, a box-like structure forming a frame 35 which is open at the outer side adapting it to be closed by a flanged cover plate 35. A recess 36 is formed at each end of the frame with which co-operates a complementary recess 37 formed in the cover flanges 40 with the result that, when the cover is secured removably in place, as with the aid of bolts 38, the two recesses unite to form a slot. Through the slot thus formed at each 45 end of the frame is slidably extended the bar 20 whereon is carried the foot rest C. At the forward end of the frame is provided an extension flange 39 providing a support for a block 40 on which is rested the forward end 50 of the bar. A locking plate 41, which is shown as secured to the inner side of the rear frame wall adjacent its upper side, is adapted to engage successively within each of the bar notches 22 so as to hold the bar in a given 55 position of adjustment. The bar is further secured against play as by means of a channeled shoe 25 which is so positioned within the frame as to receive a lateral throat from one end of a set screw 42 which extends through a threaded opening 43 in the cover plate 35.

Among the principle advantages accruing 60 from this invention is the ease and small expense with which the foot rest may be constructed and assembled. It may also be formed to present an ornamental and attrac-

tive appearance, and its friction faces reinforced with durable materials. The support thus provided for the foot rest is ample for all purposes, and the shifting operation is readily accomplished, the only preliminary step being a slight tilting sufficient to disengage the bar from the locking plate. It is apparent, therefore, that the present foot rest embodies numerous features which may be combined together, or be used separately in different combinations if desired, and that the form and relationing of the various parts may also be modified within considerable limits without departing from the spirit of my invention, as set forth in 80 the claims following:

I claim:

1. In a device of the kind described, the combination of a frame, a bar slidably mounted within the frame and adapted to 85 carry a foot rest, and means for exerting a lateral pressure on the bar, comprising a shoe in engagement therewith and an adjusting device having a screw-threaded connection with the frame adapted to vary the 90 pressure of the shoe upon the bar, substantially as described.

2. In a device of the kind described, the combination of a frame having slotted end walls, a bar extended through the frame 95 and slots at opposite ends thereof, the engaging faces of the bar and end walls being such as to prevent rotation of the bar relative to the frame and to permit the former to slide freely through the latter, the slot 100 at one frame end being slightly longer in a vertical direction than the other, locking means carried by the frame adjacent the upper edge of the longer slot and so disposed relative thereto as to receive engagement from the upper edge of the bar wherein are formed notches, a block adjacent the lower edge of the other slot forming a fulcrum upon which the bar may rock to lift its upper edge into engagement with the 110 locking means, and a shoe rest carried by the bar end proximate to the fulcrum block, substantially as described.

3. In a device of the kind described, the combination of a frame, a bar longitudinally slidable within the frame, a foot rest carried on the forward end of the bar, a friction block at the forward end of the frame providing a fulcrum bearing such that the bar may be rocked thereon to lift 115 its rearward end, and means fixedly associated with the rearward end of the frame for engaging with a notch in the top edge of the bar to lock the same against longitudinal movement, substantially as described.

4. In a device of the kind described, the combination of a frame, a bar slidably mounted therewithin, a foot rest carried at the forward end of the bar, and means 130

sitioned at the rear end of the frame adapted to engage with the upper edge of the bar wherein are formed a plurality of notches, the said means serving to lock the bar in any selected position of longitudinal adjustment, substantially as described.

5. In a device of the kind described, the combination of a frame wherein is mounted a longitudinally shiftable and vertically 10 tilttable bar having on its forward end a foot rest, and means carried by the frame adapted to be normally engaged by one edge of the bar wherein are formed a plurality of transverse notches, the said means acting 15 normally to lock the bar against longitudinal movement when the bar is in a selected forward position of adjustment, substantially as described.

6. In a device of the kind described, the

combination of a frame wherein is slidably 20 mounted a bar whose forward end is normally protruded from the frame, a foot rest carried on the forward end of the bar, supporting means associated with the frame providing a fulcrum on which the bar may 25 rock, and other means rearwardly of the fulcrum engageable with a notch in the bar when its forward end is subjected to the action of gravity, substantially as described.

7. In a device of the kind described, the 30 combination of a frame, a bar slidably but non-rotatably mounted therein, a shoe mounted within the frame and bearing laterally against the bar with an adjustable pressure, and means for locking the bar in 35 a selected forward position of adjustment, substantially as described.

CHARLES S. SMITH.
